UNITED STATES PATENT OFFICE

CARLTON B. SHARPE, OF SAGINAW, MICHIGAN

VACUUM VENTILATING STOVE HOOD

Application filed September 20, 1929. Serial No. 394,024.

The present invention contemplates the provision of a vacuum ventilating stove hood, which embodies amongst other features, a hood adapted to be supported above the cooking stove, and associated with means for eliminating the heated air, odor and other fumes from the cooking surface of the stove.

In carrying out the invention I contemplate the use of a hood adapted to be arranged above the cooking stove, and within which hood is arranged a fan for creating a vacuum, whereby heated air, odors and other fumes are carried away from the cooking surface of the stove, and out of the room in which the stove is located, while also arranged within the hood is a lamp for directing its rays upon the stove.

The nature and advantages of the invention will be better understood when the following detail description is read in connection with the accompanying drawings, the invention residing in the construction, combination and arrangement of parts as claimed.

In the drawings forming part of this application like numerals of reference indicate similar parts in the several views, and wherein:

Figure 1 is a side elevation of the invention, showing a portion of a stove by dotted lines.

Figure 2 is a fragmentary view taken at a right angle to Figure 1.

Figure 3 is a sectional view on line 3—3 of Figure 2.

Figure 4 is a bottom plan view partly broken away.

The ventilating device forming the subject matter of the present invention embodies a hood 10 which may vary in size and configuration without departing from the inventive idea. The hood is adapted to be supported an appreciable distance above an ordinary cook stove indicated generally at 11, and for this purpose I preferably employ a pair of spaced standards, each including telescopic sections 12 and 13 respectively. By reason of this construction, the distance of the hood above the stove can be varied, the sections of each standard being held fixed relatively by a suitable set screw 14. The adjustable section 13 of each standard is con-

nected to a supporting bar 15 arranged within the hood by means of an elbow 16, and these supporting bars 15 are mounted within the hood in any suitable manner preferably by rings 17.

Arranged within the hood is a frusto-conical shaped deflector 18 for directing the heated air, odor and fumes about the stove surface into the hood, and this heated air and the like are subsequently conveyed to the chimney (not shown) by an outlet pipe 17, projecting laterally from the hood as illustrated. Suitable brackets 20 support an electric motor 21 within the hood, and associated with this motor is a fan 22 arranged directly above the opening of the deflector 18. Consequently when the fan is in operation, the heated air and fumes about the stove surface are drawn by a vacuum into the hood 10, from which they subsequently pass into the chimney through the outlet flue 19. Rising from the motor and projecting through openings in the top of the hood are small pipes 23 through which the motor can be properly lubricated from time to time as the occasion may require.

Also located within the hood 10 adjacent the lower forward edge thereof is an electric light bulb 24 which is arranged in a suitable reflector 25, whereby the light rays are directed downwardly in the direction of the cooking stove 11. The electric wires 26 for the lamp are connected with a switch 27, while similar wires 28 for the motor are also connected with the same switch. The switch 27 is preferably of the push button type, and these buttons are indicated at 29. Leading from the switch is a cable 30 which has associated therewith a socket 31 adapted to accommodate the usual plug leading from a source of current.

By reason of the construction illustrated and described, it is manifest that the hood 10 may be adjusted toward and away from the stove, and held in its given position by tightening the set screw 14. When the switch is closed to the lamp 24, the latter is so located as to direct its light rays over the stove 11. When the switch is closed to the electric

motor 21, the fan is operated to create a vacuum and thereby draw the heated air and fumes from the cooking surface of the stove within the hood 10, passing through the deflector 18, and leaving the hood through the flue 19.

While it is believed that from the foregoing description, the nature and advantages of the invention will be readily apparent, I desire to have it understood that I do not limit myself to what is herein shown and described and that such changes may be resorted to when desired as fall within the scope of what is claimed.

15 What I claim is:—

1. A vacuum ventilating stove hood, comprising a hood adapted to be arranged above a stove, means for adjustably supporting the hood, whereby it can be arranged any desired distance above the stove, a frusto cone shaped deflector arranged within the hood and having an enlarged central opening, an electric motor within the hood, a fan supported by said motor and arranged directly above said opening in the deflector, whereby a vacuum is created and the heated air and fumes drawn from the cooking surface of the stove into the hood, and an outlet flue projecting from said hood.
- 20 2. A vacuum ventilating stove hood comprising in combination a hood open at its bottom and adapted to be arranged directly above the stove, a pair of spaced standards adapted to repose upon the floor wholly to one side of the stove and hood, one side of the hood having spaced openings, supporting bars arranged within the hood and attached to the opposed walls thereof and projecting through said openings, one bar for each standard, elbows connecting the adjacent ends of said bars and standards whereby the hood is supported upon the stove, means arranged within the hood for creating a vacuum and thereby drawing the heated air and fumes from the cooking surface of the stove into the hood, and an outlet flue projecting from the hood.

In testimony whereof I affix my signature.
CARLTON B. SHARPE.
